UNITED STATES PATENT OFFICE.

STACY B. HASELTINE, OF CHICAGO, ILLINOIS, ASSIGNOR TO WILLIAM H. MINER, OF CHAZY, NEW YORK.

HAND BRAKE FOR RAILWAY CARS.

Application filed May 8, 1922. Serial No. 559,167.

To all whom it may concern:

Be it known that I, STACY B. HASELTINE, a citizen of the United States, residing at Chicago, in the county of Cook and State 5 of Illinois, have invented a certain new and useful Improvement in Hand Brakes for Railway Cars, of which the following is a full, clear, concise, and exact description, reference being had to the accompanying 10 drawings, forming a part of this specification.

This invention relates to improvements in hand brakes for railway cars.

One object of the invention is to provide 15 an efficient hand brake mechanism of the ratcheting type and more particularly one in which engagement between the pawl and ratchet wheel is always made quickly without possibility of undue lost motion or shortening of the power stroke of the operating handle.

Another object of the invention is to provide an arrangement for holding the winding member against accidental reverse rotation, which arrangement includes a holding dog or latch adapted to be released by the same operating handle which is employed in applying the brake in combination with efficient means to prevent such release 30 accidentally at any time during the application of the brakes.

Other objects of the invention will more clearly appear from the description and claims hereinafter following.

In the drawing forming a part of this specification, Figure 1 is a vertical, sectional view of an improved hand brake shown applied to the end wall of a car, the section corresponding substantially to 35 the section line 1-1 of Figure 3. Figure 2 is a similar vertical, section corresponding to the section line 2-2 of Figure 3. Figure 3 is a vertical, sectional view taken perpendicular to the car wall substantially diametrically of the mechanism and corresponding to the line 3-3 of Figure 1. And Figure 4 is a horizontal, sectional view corresponding to the line 4-4 of Figure 1 illustrating certain details, parts being 50 broken away.

In said drawing, the end wall of the car is indicated at 10 and to which the improved mechanism is adopted to be secured. The improved mechanism includes a main outer shell or casing designated generally by the

reference character A, the same being of cylindrical form having an integral outer end wall 11 and securing flanges 12-12 at its inner end by which it is riveted to the wall. The casing A is provided at the 60 bottom thereof with a longitudinally extending opening 13 to permit entrance of the chain and also to allow for the back and forth movements of the operating handle. At its inner end, the casing A is 65 formed with a partial segmental shaped wall 14 of appreciably less than half of the area of the casing, the remainder of the back wall being completed by a separate member 15 so shaped as to complete the back wall, 70 said member 15 preferably having beveled edges 16-16 engaging with corresponding beveled edges on the casing A, so that the member 15 will lie flush with the back wall 14 when the casing is attached to the car 75 wall.

The outer end wall 11 of the casing is formed with an inwardly extending integral stud 17 and an opposing oppositely extending stud 18 is formed on the member 15, as 80 clearly shown in Figure 3. A journal for the winding drum is provided by a tubular element 19 which fits over the two studs 17 and 18 and is preferably riveted to the stud 18 as by the rivet 20. In this manner it will be noted that I obtain an elongated journal thus providing the maximum length of bearing surface for the rotatable chain winding drum B.

The drum B has a main winding section 90 proper 21 with an annular flange 22 at its inner end and a partition-forming flange 23 at the opposite end of the winding section 21. On one side and preferably adjacent the partition flange 23, the drum B is formed with an integral lug 24 notched as indicated at 25 to provide a hook for the end link 26 of the chain running to the usual sheave wheel at the bottom of the car. The hook-shaped lug 24 is so positioned that the link 26 may be hooked thereover before the drum is telescoped over the tubular bearing 19 and when assembled with the latter the link 26 is locked in position as clearly shown in Figure 3. It will be noted that the partition flange 23, in effect, divides the casing into two chambers, one for the chain winding and the other for the ratcheting arrangement.

To the right of the flange 23, as viewed in 110

Figure 3, the drum member B is provided with a circular bearing 27 relatively narrow. To the right of the bearing 27, the drum member B is formed with diametrically disposed curved keying lugs 28—28 as shown in Figure 1 and over which is assembled the ratchet wheel 29, thus interlocking the latter with the drum member B so that they rotate simultaneously. To the right of the key lugs 28, as viewed in Figure 3, the drum member B is provided with an additional bearing 30 of lesser diameter than the bearing 27.

The bearings 27 and 30 support a carrier or fulcrum member C, the latter having spaced side walls 31—31 with journal bearing openings therein corresponding to the bearings 27 and 30 and an arcuate connecting web 32 between the flanges 31. Pivotally supported on the carrier C is a pawl D, as by means of the pivot 33. Said pawl D is provided with a tooth 34 normally out of engagement with but adapted to engage the peripheral teeth of the ratchet wheel 29, as clearly indicated in Figure 1. On the opposite side of the pivot 33 to the tooth 34, the pawl D is formed with a curved tail-piece 35 having an OG curved surface 36, as shown in Figure 1.

The carrier C is formed with a pair of radially extending ears or flanges 37—37 between which is pivotally mounted as by the pivot 38, the operating handle or lever E. The latter is formed with a curved projection or finger 39 of suitable contour to operate with the OG curved surface 36 of the pawl D. With this arrangement, when the operating handle E is pulled toward the left, as viewed in Figure 1, the lug or finger 39 will swing the tail-piece 35 of the pawl D and throw the tooth of the latter into engagement with the ratchet wheel. As will be clear from an inspection of Figure 1, a very slight angular movement of the handle E on its pivot will produce a greater and therefore quicker angular movement of the tooth 34 on account of the relatively short radius from the pivot of the pawl D to the point of effective engagement of the handle and tail-piece 35. This is of importance in the operation of a brake mechanism, inasmuch as it minimizes the possible lost motion in effecting operative engagement with the ratchet wheel each time a power stroke is made.

To hold the drum and ratchet wheel against rotation in a reverse or unwinding direction, I have provided a locking dog or latch F, the same being pivoted on a rivet 40 which is supported at its outer end in the end wall 11, as shown in Figure 4 and at its inner end by means of a radially extending flange 41 integral with the casing A as shown in the same figure. Said dog F is provided with a tooth 42 adapted to engage with the ratchet

wheel as shown in Figure 1 and has a relatively heavy extension 43 passing outwardly through an opening 44 in the casing A, the latter being laterally offset at this point to form a hood or weather shield for the dog as indicated at 45 in Figure 1. The heavy extension 43 is continued downwardly with a tail-piece 46 having a rounded lower cam edge 47. With the arrangement thus far described, it will be seen that the latch or dog F is gravity influenced to automatically engage with the ratchet wheel.

To disengage the tooth 42 of the dog from the ratchet wheel, the operating handle E has a relatively heavy lug 48 extended toward the tail-piece of the dog F, said lug 48 having a curved surface 49 adapted to engage the rounded edge 47 of the dog and, when the handle is swung a sufficient distance counterclockwise, as viewed in Figure 1, will engage the dog F and swing it so as to pull the tooth 42 away from the ratchet wheel. In this connection, it will be observed that I obtain a relatively high leverage ratio in disengaging the dog from the ratchet wheel, which is of importance in facilitating release of the brake rapidly and particularly where the brake chain has been placed under a high tension and undercut teeth are employed on the ratchet wheel, as shown in Figure 1, since, during the release, the ratchet wheel must be given slight amount of further rotation in a winding direction before the dog tooth can be disengaged.

In order to prevent accidental disengagement of the dog from the ratchet wheel when the brakeman is using the handle E, I provide the following arrangement. Pivotally supported between the end wall 11 of the casing and the inturned flange 41 previously referred to, as by means of the rivet 50 shown in Figure 4, is a sector-like block 51. The latter is provided with a laterally extended finger piece or pin 52 movable within an arcuate slot 53 formed in the end wall 11 of the casing, as shown best in Figures 1 and 4. When the block 51 is in the full line position shown in Figure 1, at which time the pin 52 is at the lower end of the slot 53, the block acts as a limiting stop to movements of the pawl D and consequently the carrier C in a counter-clockwise direction and the parts are so positioned that when the pawl and carrier D are thus stopped in their movements, the lug 48 of the operating handle will not quite engage the tail-piece of the dog F, as shown in Figure 1. When the brakeman desires to release the brakes, he swings the gravity block 51 to its other extreme position as shown by the dotted lines in Figure 1, thus permitting the operating handle and carrier C and pawl D to swing farther in a counter-clockwise direction and sufficiently for the

lug 48 of the handle to engage the dog F and in turn disengage the latter from the ratchet wheel.

From the preceding description, it will be seen that I provide for quick engagement of the operating pawl to effect winding; provide for relatively powerful leverage ratio to effect disengagement of the locking dog from the ratchet wheel; and also employ only one operating lever or handle for effecting both the winding up of the brake chain and the release thereof. In addition, the arrangement also prevents accidental release as previously described.

I have herein shown and described what I now consider the preferred manner of carrying out the invention, but the same is merely illustrative and I contemplate all changes and modifications that come within the scope of the claims appended hereto.

I claim:

1. In a hand brake for cars and the like, the combination with a rotatable member; of a ratchet wheel rotatable in unison therewith; a carrier oscillatably mounted with respect to said wheel; a pawl pivotally mounted on said carrier and cooperable with said ratchet wheel; an operating handle mounted on said carrier for movement relative thereto and cooperable with said pawl to move it to operative position; and locking means for preventing rotation of said member accidentally in an unwinding direction.

2. In a hand brake for cars and the like, the combination with a rotatable member; of a ratchet wheel rotatable in unison therewith; a carrier oscillatably mounted with respect to said wheel; a pawl pivotally mounted on said carrier and cooperable with said ratchet wheel; an operating handle pivoted on said carrier at a different point and cooperable with said pawl to move it to operative position; locking means for preventing rotation of said member accidentally in an unwinding direction; and means on said handle cooperable with said locking means to render the latter inoperative when said handle is moved against said locking means.

3. In a hand brake for cars and the like, the combination with a rotatable member for effecting tightening of the brake chain; of a ratchet wheel rotatable in unison therewith; a carrier oscillatable with respect to said wheel; a pawl pivotally mounted on said carrier and provided with a tooth cooperable with the ratchet wheel, said pawl being provided also on the opposite side of its pivot to that of the tooth, with a tail-piece; an operating handle pivotally mounted on said carrier at a different point and provided with means to engage said tail-piece of the pawl and throw the latter into operative relation with the ratchet wheel; and locking means

for preventing accidental rotation of said member in a reverse direction.

4. In a hand brake for cars and the like, the combination with a rotatable member for effecting tightening of the brake chain; of a ratchet wheel rotatable in unison therewith; a carrier oscillatable with respect to said wheel; a pawl pivotally mounted on said carrier and provided with a tooth cooperable with the ratchet wheel, said pawl being provided also on the opposite side of its pivot to that of the tooth with a tail-piece; an operating handle pivotally mounted on said carrier at a different point and provided with means to engage said tail-piece of the pawl to throw the latter into operative relation with the ratchet wheel; locking means for preventing accidental rotation of said member in a reverse direction; and means on said handle cooperable with said locking means to render the latter inoperative when the handle is swung into engagement with said locking means.

5. In a hand brake of the character described, the combination with a rotatable member for effecting tightening of the brake chain; of ratchet mechanism for effecting step by step rotation of said member, said mechanism including an operating handle movable in one direction to actuate the mechanism; locking means to prevent accidental rotation of said member in an unwinding direction; cooperable means on said handle and locking means to render the latter inoperative when said handle is moved in a direction opposite to that necessary to actuate said mechanism; and a shiftable safety device adapted to prevent cooperative relation between said locking means and means on the handle cooperable therewith.

6. In a hand brake of the character described, the combination with a member for effecting tightening of the brake chain; of ratcheting mechanism for effecting step by step rotation of said member, said mechanism including an operating handle movable in one direction to actuate the mechanism; locking means including a pivoted dog to prevent rotation of said member accidentally in an unwinding direction; means on said handle engageable with said dog to move the latter to inoperative position, when the handle is moved in a direction opposite to that necessary to actuate said mechanism; and an adjustable safety device adapted to prevent or permit cooperative engagement between said dog and said means on said handle cooperable therewith.

7. In a hand brake of the character described, the combination with a rotatable chain winding drum; of ratcheting means for effecting step by step rotation of said drum and including a bodily movable and pivotally mounted operating handle; means for locking said drum against rotation in

an unwinding direction and including a pivotally mounted dog having a tail-piece; an extension on said operating handle adapted to engage said tail-piece of the dog 5 to move the latter to inoperative position when the handle is moved in one direction; and a manually adjustable safety element adapted to prevent or permit cooperative relation between said extension on the 10 handle and tail-piece of the dog.

8. In a hand brake of the character described, the combination with a casing of generally cylindrical form having an integral outer end wall and adapted to be secured at its inner end to a wall of a car; of a bearing extending axially of said casing therewithin; a winding drum member rotatably mounted on said bearing and having a winding portion proper; a ratchet wheel 15 rigidly secured to said drum member; a carrier oscillatably mounted on said drum member and straddling said ratchet wheel; an operating handle pivotally mounted on said carrier; a pawl pivotally mounted on 20 said carrier at a different point and arranged to cooperate with said ratchet wheel, 25

said pawl and handle having cooperable engaging sections to actuate the pawl to operative position when the handle is pulled in one direction; a locking gravity actuated dog pivotally mounted on said casing and cooperable with said ratchet wheel to prevent rotation of the latter and drum in an unwinding direction, said dog having a tail-piece; an extension on said handle adapted to engage said tail-piece to disengage the latter from the ratchet wheel when the handle is moved in a direction opposite to that first mentioned; and a block pivotally mounted on said casing at a point intermediate the dog and the operating handle, said block in one position preventing engagement between the handle and the dog and, in another position, permitting such engagement.

In witness that I claim the foregoing I have hereunto subscribed my name this 18th day of April 1922.

STACY B. HASELTINE.
